C. D. FATOR.
OIL WELL PUMP.
APPLICATION FILED MAR. 18, 1921.

1,419,495.

Patented June 13, 1922.

UNITED STATES PATENT OFFICE.

CHARLES DIBRELL FATOR, OF SAN ANTONIO, TEXAS.

OIL-WELL PUMP.

1,419,495.

Specification of Letters Patent. Patented June 13, 1922.

Application filed March 18, 1921. Serial No. 453,218.

To all whom it may concern:

Be it known that I, CHARLES DIBRELL FATOR, a citizen of the United States, residing at San Antonio, in the county of Bexar 5 and State of Texas, have invented certain new and useful Improvements in Oil-Well Pumps, of which the following is a specification.

This invention relates to pumps used in 10 connection with wells for oil and other fluid; and it consists in the novel construction and combination of the parts hereinafter fully described and claimed whereby the pump barrel is anchored or locked to the well 15 liner while the pump is at work, and is unlocked at will when the pump and other parts are to be raised in the well.

In the drawings, Figure 1 is a vertical section through the liner of an oil well provided 20 with a pump having devices for anchoring it to the liner according to this invention. Fig. 2 is a cross-section, taken on the line 2—2 in Fig. 1. Fig. 3 is a cross-section taken on the line 3—3 in Fig. 1. Fig. 4 is a detail showing how the locking 25 arms lock the barrel to the liner.

The well is provided with a perforated liner 5. The pump barrel 6 is arranged inside the liner, and 7 is a tubular pump rod 30 which operates the pump, and which also affords a delivery passage for the oil or other liquid which is pumped from the well. The working parts of the pump and its valves are of any approved construction.

35 In operating pumps as ordinarily constructed the delivery valves or other parts sometimes become partially obstructed by sand or other material, and when the pump rod is raised in pumping the pump barrel 40 is sometimes raised with it to some extent, which is a disadvantage in working the pump.

In carrying out this invention, a tubular guide 8 is secured to the upper end of the 45 pump barrel by a collar 9, and it has a guide collar 10 secured on its upper end portion.

The pump rod 7 works freely inside the guide 8. A collar 12 is secured to the guide 8 and rests on the collar 9. Locking arms 14 50 are pivoted by pins 15 to the collar 12, and have serrated faces 16 at their outer ends for engaging with the liner 5. Three arms are preferably provided, and they are normally held in their raised positions, clear 55 of the liner, by any suitable spring or springs 17. A locking pipe 18 is provided, and a

conical locking ring 19 is secured to the lower end of this pipe, and is slidable freely on the tubular guide 8. The locking ring 19 has a shoulder 20 at its upper end which 60 projects under a collar 21 on the tubular guide, and forms a means for raising the pump. The middle and upper parts of the locking pipe 18 are guided by the collar 10 on the guide pipe.

65 The locking pipe has a bush 24 at its upper part, and anti-friction rollers 25 are journaled in this bush, and hold the pump rod 7 axially in line with the pump barrel, and permit the pump rod to slide freely.

70 A collar 26 is secured on the pump rod 7, below the bush 24, and when the pump barrel is to be raised, the collar 26 engages with the bush 24, so that the pump is lifted by means of the pump rod. Flexible connections or 75 chains 27 are secured to the locking pipe and to the ends of the locking arms, and 28 are springs for taking up the slack of these chains, so that they will always work to good advantage. These chains raise the 80 arms out of engagement with the liner before the shoulder 20 touches the collar 21.

When the parts are in the positions shown 85 in Fig. 1, the pump barrel 6 is not locked to the liner 5, and can be raised and lowered. When the locking pipe is lowered, as shown in Fig. 4, the conical locking ring 19 forces the locking arms outwardly into engagement with the liner 5, and prevents the pump barrel from rising until the parts are restored 90 to the positions shown in Fig. 1 by raising the locking pipe.

The pump is supported by the bottom of the well, so that it cannot slide downwardly.

95 What I claim is:

1. The combination, with a well liner, and a pump arranged therein and provided with a slidable operating rod; of locking arms pivotally connected with the pump barrel, a guide secured to the pump barrel, and a locking device slidable on the said guide and operating when moved in one direction to press the said arms outwardly into locking engagement with the said well liner, said locking device being held clear of the slid- 100 able pump rod by the said guide.

2. The combination, with a well liner, and a pump arranged therein; of a tubular guide secured to the pump barrel, locking arms having their lower ends pivotally connected 105 with the pump barrel, and a locking device slidable on the tubular guide and operating,

when lowered, to press the said arms outwardly into locking engagement with the liner.

3. The combination, with a well liner, and a pump arranged therein; of a tubular guide secured to the pump barrel and provided with a projection on its lower end portion, locking arms having their lower ends pivotally connected with the pump barrel, and a conical locking ring slidable vertically on the tubular guide and operating to press the said arms outwardly when lowered and to raise the pump, by engagement with the said projection, when raised.
4. The combination with a well liner, and a pump arranged therein; of a tubular guide secured to the pump barrel, locking arms having their lower ends pivotally connected with the pump barrel, a locking device for pressing the said arms outwardly when lowered, and flexible connections between the free end portions of the arms and the locking device which pull the said arms inwardly out of engagement with the liner when the locking device is raised out of engagement with the locking arms.
5. The combination, with a well liner, and a pump arranged therein; of a tubular guide secured to the barrel and having a projecting guide collar on its upper part, locking arms having their lower ends pivotally connected with the pump barrel, a locking pipe slidable vertically over the said guide collar and having at its lower end a conical locking ring slidable on the tubular guide

and operating to press the said arms outwardly when lowered, and means for raising and lowering the said locking pipe.

6. The combination, with a well liner, and a pump arranged therein and provided with a pump rod provided with a projection; of a tubular guide secured to the pump barrel and provided with a projection, locking arms having their lower ends pivotally connected with the pump barrel, and a locking pipe slidable over the tubular guide and having at its lower end a conical ring which presses the locking arms outwardly when the locking pipe is lowered and which raises the pump by engagement with the said projection on the tubular guide when the locking pipe is raised, said locking pipe having also at its upper part an internal projection which is engaged by the said projection on the pump rod when the pump rod is raised, so that the locking pipe and the pump are raised and lowered by the pump rod.

7. The combination, with a well liner; and a pump arranged therein; of locking arms having their lower ends pivotally connected with the pump barrel, springs which normally hold the free end portions of the locking arms out of engagement with the well liner, and a slidable locking device which operates, when lowered, to press the said arms outwardly into locking engagement with the liner.

In testimony whereof I have affixed my signature.

CHAS. DIBRELL FATOR.
